CONTAINER FILL CHECKING MACHINE

Alfred L. Kronquest, Syracuse, N. Y., assignor to
 Continental Can Company, Inc., New York,
 N. Y., a corporation of New York

Application December 19, 1941, Serial No. 423,697

16 Claims. (Cl. 226—22)

The invention relates to new and useful improvements in liquid level testing equipment and primarily seeks to provide a novel machine structure capable of rapidly and efficiently testing the level of the fill in liquid filled containers, drawing off and reclaiming fill surpluses, and automatically rejecting all slack filled containers.

In modern practices involving the packaging of liquids, automatic filling machines are employed in an effort to rapidly and accurately fill the liquid containers. Machines of this type are generally provided with means for regulating the volume of liquid filled into the containers so that each will contain the desired, predetermined quantity. In spite of the volumetric adjustments on and the relatively efficient operation of these machines, variations in the volume of liquid filled into containers often occur with the result that some containers will contain more than the intended amount whereas others will be slack filled. Obviously, surplus fills mean unnecessary losses to the producer, whereas slack fills are very objectionable to and will not consciously be tolerated by the consumer. It is the purpose of the present invention to provide a simple and inexpensively constructed machine in which both of these objectionable conditions will be avoided, first by drawing off and saving all fill surpluses, and second by detecting and rejecting all slack filled containers, thereby permitting only properly filled containers to be fed on for distribution and consumer use.

In its more detailed nature the invention resides in providing a machine structure wherein are provided filled container feed-in ways, properly filled container delivery ways, and slack filled container rejecting ways, means for moving containers onto and over said ways, a testing unit including a surplus liquid draw off tube and a pair of electrodes, means for bringing about relative movement between a container and said unit to cause the tube and electrodes to project to the predetermined proper fill level in the container so that any surplus liquid will be drawn off through said tube and the contact of the electrodes with the liquid will complete an electrical circuit effective to control means for assuring delivery of properly filled containers over the delivery ways, or in the case of slack filled containers failing to complete said circuit and thereby to render effective means for rejecting said slack filled containers over the rejecting ways.

Another object of the invention is to provide a machine structure of the character described

including a novel turret structure whereon is mounted a plurality of said testing units and an individual pad for receiving each container to be tested, said pads being vertically reciprocable to present containers to said units, and all surplus draw off tubes being connected with a common draw off duct disposed centrally of the turret.

Another object of the invention is to provide a machine structure of the character stated wherein is embodied means normally effective to reject containers onto the rejection ways, and means controlled by said electrodes for rendering the normally effective container rejecting means ineffective to reject properly filled containers.

Another object of the invention is to provide a machine of the character stated in which the slack filled container rejecting means includes stationary diverter cam means, and in which novel latch means controlled by said electrodes serve to hold properly filled containers elevated above said cam means to render said cam means ineffective and cause said containers to be delivered to the delivery ways.

With the above and other objects in view that will hereinafter appear, the nature of the invention will be more fully understood by following the detailed description, the appended claims, and the several views illustrated in the accompanying drawings.

Figure 1 is a plan view of a machine embodying the invention, a portion of the turret being illustrated in horizontal section.

Figure 2 is a vertical cross section taken substantially on the line 2—2 on Figure 1.

Figure 3 is a fragmentary horizontal section illustrating a part of the drive for the timing screw.

Figure 4 is a fragmentary cross section taken on the line 4—4 on Figure 1.

Figure 5 is an enlarged fragmentary sectional view illustrating a container lifted into the testing position.

Figure 6 is a fragmentary horizontal section taken on the line 6—6 on Figure 5.

Figure 7 is an inverted plan view of a fragment of the chambered insulator ring.

Figure 8 is a fragmentary face view illustrating the mounting of one of the pads.

Figure 9 is a somewhat diagrammatic horizontal sectional view illustrating the positioning of the latch tripping cam plate and roller equipments and the relation thereof to the lifting and lowering portions of the pad position controlling

cam, the section being taken on the line 9—9 on Figure 2.

Figure 10 is a diagrammatic development of the pad position controlling cam.

Figure 11 is a fragmentary vertical sectional view illustrating a simple basic form of surplus draw-off tube with its lower extremity disposed at the normal fill level in a container.

In the machine herein disclosed as an example of embodiment of the invention, there is included a frame having a top or table portion A over which filled containers are fed into the machine by feed-in mechanism generally designated B, and transferred by a star wheel or transfer turret C to the main turret D whereon the containers are tested to determine whether they are over filled or under filled and on which any contained liquid surpluses are drawn off. Slack filled containers are discharged through a rejection pass E, while properly filled containers pass on and are transferred by the star wheel or transfer turret F onto the delivery ways or feed-off mechanism generally designated G. See Figure 1.

While it is to be understood that the machine is adaptable for use in the testing of various forms of containers, the containers herein illustrated are of the gallon can type such as are employed in the packaging of syrups, beverages or the like. These containers include a body portion 5 to the upper end of which is affixed a cone top 6 terminating in a restricted pouring throat 7. The testing of the liquid level in said containers and the drawing off of any liquid surpluses from said containers is effected through the restricted throats 7.

In its more detailed nature, the machine includes a framing 8 having a table or top portion 9 which is cut out, as at 10, to accommodate the main rotary turret D. The framing includes a central vertical bearing hub 11 for the turret D, vertical bearings 12 for the star wheel C, and vertical bearings 13 for the star wheel F. See Figure 2.

The main turret D includes a central, hollow column or shaft 14 which is rotatably supported in the bearing 11 and has a turret body 15 secured thereon in position for resting upon the top of said bearing 11. The turret body is equipped with six equi-distantly spaced pad stem bearings 16 in the peripheral portion thereof and includes a depending skirt 17 equipped with a spur gear rim portion 18 at its lower end.

While the machine herein illustrated is equipped with a six station turret, it is to be understood that the number of stations provided on the turret can be varied if desired.

The main turret D also includes an upwardly extended portion 19 equipped with peripheral open pockets 20 for receiving containers transferred to the turret by the star wheel C. One such pocket is disposed opposite each stem bearing 16, and centered beneath each pocket is a container supporting pad 21 equipped with a depending plunger or stem 22 which is vertically reciprocable in one of the turret bearings 16. Each of the stems 22 is equipped with a roller 23 mounted at its lower end engageable on a cam ring 24 fixed, as at 25, upon the machine frame.

Each stem 22 is held against movement about its axis by a lug 26 secured to the stem and engaged in a vertical slot 27 formed in the turret body 15. A retractile spring 28 anchored to the turret and connected to the under surface of the respective pad 21 yieldably holds each stem roller 23 against the cam 24. Each stem 22 is equipped

with a latch receiving recess 29 in the inwardly directed wall portion thereof, and these latch recesses serve a purpose which will be explained hereinafter. See Figures 2, 5 and 8.

5 The transfer turret or star wheel C comprises a vertical shaft 30 rotatably mounted in the bearings 12 and having a bevel gear 31 secured at its lower end. A star wheel or turret rotor 32 is secured at the upper end of the shaft and is 10 equipped with peripheral pockets 33 for receiving the filled containers from the feed-in mechanism B for transfer to the turret pockets 20. See Figure 2.

15 The transfer turret or star wheel F comprises a vertical shaft 34 rotatable in the bearings 13 and having a spur gear 35 secured at its lower end. The spur gear meshes with and imparts rotation to the turret rim gear 18 and a bevel gear ring 36 is secured to said spur gear 35. See Figure 2.

20 The bevel and spur gears 31, 35 and 36 are driven through bevel pinions 37 mounted on a drive shaft 38 which is rotatable in frame bearings 39. The shaft 38 is driven through a bevel gear couple 40 from a driver shaft 41 rotatable in frame bearings 42, said driver shaft being driven through sprocket and chain connections 43, and through an overload release equipment 44, from the motor or other suitable source of 25 power (not shown). The source of power preferably comprises an electric motor mounted directly on the machine framing. The shaft 41 also carries a driver sprocket 45, the purpose of which will later become apparent. See Figures 30 1, 2 and 4.

35 Above the pockets 20, the main turret is provided with a superstructure or additional upward extension 46 having a horizontal ring top 47 equipped with six equidistantly spaced clamp 40 bearings 48, one thereof being disposed centrally over each of the container supporting and lifting and lowering pads 21. In each of the clamp bearings 48 there is secured an insulator hub 49 having a removable cover 50 and being 45 recessed to receive two contact members 51 disposed in spaced relation and from which depend two electrodes or contact needles 52.

40 The electrodes are disposed close together and close to a bore 53 extending vertically through 50 the hub 48. Each pair of contacts 51 are connected by leads 54 extending through sheathed conductors with the contacts 55 disposed in spaced relation within the chamber in an insulator ring composed of upper and lower separable 55 plates 56 and 57, said contacts 55 being electrically connected with concentrically spaced contact sectors 58 secured beneath the lower plate 57. Two said sectors 58 are provided for each 60 of the electrode sets 52, and the twelve sectors together form two concentric contact rings which are continuous except for narrow insulating spacers 59 which are approximately one-eighth of an inch in width and are disposed between the ends of the individual sectors making up these contact rings. See Figure 7.

65 A sleeve 60 is mounted in the upper end of the column 14 and supports a chambered plug 61 into the bottom of which is connected a liquid surplus draw off or suction line 62, said line extending downwardly through the vertical column 14 and being connected at its lower end, as at 63, with a suction source (not shown), and at 64 with a surplus liquid recovery reservoir (not shown). A closure cap 65 is mounted over the 70 upper end of the sleeve 60 and has a bored center

hub 66 depending therefrom into the chamber in the plug 61. The cap is provided with a plurality of radially and horizontally extended clamp bearings 67 and carries a shield 68 which overlies the insulator ring 56, 57. One of the clamp bearings 67 is provided for each of the turret stations, and in each bearing is clamped a suction pipe 69. The radially projected end of each pipe is rigidly secured in a clamp member 70 which is vertically-adjustably mounted, as at 10 71, on the ring top 47.

A T-head 72 is affixed to the end of each suction pipe 69 and includes a downwardly extended split clamp leg 73 which is centered over one of the container supporting pads 21. A filled surplus draw off tube 74 is vertically-adjustably clamped in each T-head leg 73 through the medium of a clamping collar 75 threaded on the tapered and externally threaded end of said leg. At its lower extremity, each tube 74 is threaded, as at 76, into the spider web hub 77 of a test cup 78 which terminates upwardly in a feathered edge 79. See Figures 2, 5, and 6.

The electrodes 52 and the tube 74 and cup 78 of each testing or checking unit are spaced in close relation as illustrated in Figure 6 of the drawings so that all are receivable through the restricted throat 7 of a container.

It will be apparent by reference to Figure 10 of the drawings that the pad lifting and lowering cam 24 includes a lift portion 80 followed by a dwell portion 81, a pad lowering portion 82, and a second lifting and lowering portion spaced a considerable distance from the portions 80, 81 and 82. This second lifting portion is indicated at 83 and terminates in a crest 84 followed by a lowering portion 85. The purpose of this particular formation of the lifting and lowering cam will become apparent as this description progresses.

A bracket 86 is secured upon the column 14 and supports a contact unit 87 from which a pair of spaced brushes 88 project upwardly into engagement with the contact ring sectors 58. To the brushes are connected leads 89 which extend through a sheathed conductor 90 passed through the column 14 and are connected with a source of power generally designated 91 and with a solenoid 92 secured upon the frame, as at 93, opposite the dwell portion 81 of the lifting and lowering cam 24.

The core 94 of the solenoid is link-connected, as at 95, to one end of a trip arm or lever 96 which is pivoted intermediate its ends, as at 97, the other end of said lever being held depressed by an anchored spring 98. The trip end of the lever carries a latch releasing cam plate 99 which is disposed in the path of travel of the lower ends 100 of a plurality of vertically disposed latch levers, one such latch lever being mounted on the main turret for cooperation with each of the pad stems 22.

Each of the latch levers is pivoted intermediate its ends, as at 101, on the main turret and has its upper bifurcated end 102 engaged in side recesses in a latch plunger 103 radially disposed and slide-guided, as at 104, on the main turret. A compression spring equipment 105 serves to yieldably urge each latch plunger against the associated pad stem 22 to cause the end of the plunger to engage in the latching recess 29 in that stem when these parts are brought into registering relation for holding the respective pad and stem at the fully elevated position illustrated in Figure 5.

A latch trip roller 106 is supported on a bracket 107 secured to the turret bearing 11 opposite the crest 84 of the cam 24, and this same bracket also serves as the pivotal support 97 for the trip arm 96. This roller is effective to engage the latch lever ends 100 and thereby to displace all latches which might be in the pad lift retaining position as the pads pass the position of the roller, thereby to release the latches and permit the pads to move downwardly under the control of the lowering portion 85 of the cam.

The container feed-in mechanism B includes supporting ways 108 over which travels a link belt 109, said belt serving to deliver the filled 15 containers 5 into the machine. The link belt passes over an idler sprocket 110 on the machine table and is driven from any suitable source of power (not shown). The supporting ways 108 are flanked at one side by a timing screw 112 having trunnion bearing, as at 113, in a housing 114 secured upon the machine table. The screw is driven by a bevel gear couple 115 from a shaft 116 having rotatable bearing, as at 117, in the housing 114, said shaft also carrying a spur gear 118 to which rotation is imparted by a spur gear 119 secured upon a shaft 120 which is rotatable in a housing bearing 121 and driven by sprocket and chain connections 122 from the shaft 38 hereinbefore referred to. The ways 108 are flanked at the other side by fixed guide walls 123 and a yieldably mounted guide wall 124 disposed opposite the timing screw 112.

Arcuate guide walls 125 partially surround the main turret and extend around to the slack filled container rejection pass E. Opposite the entrance into the rejection pass E, the machine frame rigidly supports stripper or diverter cams 126, said cams being rigidly supported and extending between the upper and lower turret body flanges in which the turret pockets 20 are formed. These cams are separated to provide an opening 127 therebetween for permitting passage of the stems 22 of all pads which are held in the elevated position by latches 103 when they reach this point. It is to be understood that all container supporting pads 21 which might be in the lowered position will pass under the cams 126 so that these cams will strip containers from such lowered pads and divert or reject them into the rejection pass E.

The rejection pass E includes ways 128 for supporting rejected containers and which are spaced, as at 129, to receive between them a block chain 130 which passes over idler sprockets 131 and over the driver sprocket 45 secured upon the shaft 41 previously referred to. The ways 128 are flanked by fixed guides 132 and it will be understood that all rejected containers which are diverted onto these ways will be carried away by the chain 130.

Fixedly mounted arcuate guides 133 partially surround the turret beyond the rejection pass E, and a yieldable arcuate wall 134 normally connects the arcuate guides 125 with the guides 133. The yieldable wall 134 is normally held in place by spring means 135 but will be deflected by container contact whenever a container is rejected and diverted into the rejection pass E, springing back again to its normal position after each rejected container has passed through onto the ways 128.

The feed-off or delivery means G for the properly filled containers includes an arcuate fixed guide wall 138 merging with a fixed flank wall 75 139 and which directs the properly filled con-

ainers onto the feed-out ways 140 over which the containers are fed away by a link belt 141. The link belt 141 passes over an idler sprocket 142 which is supported on the machine table and is driven from any suitable source of power (not shown).

In Figure 11 of the drawings there is illustrated a simpler form of surplus draw-off tube structure in which the tube 74a has its lower or terminal end portion disposed at the level of normal fill in the container 5a shown as lifted for a level testing operation. While the invention broadly embraces the use of any form of tube structure in which the effective or level determining inlet is disposed at the normal fill level in the manner stated, the specific form of cup structure herein disclosed as the effective level determining means is not herein specifically claimed, this cup structure being the invention of LaVerne Edward Cliffcorn and covered in the application for U. S. Letters Patent, Serial No. 425,219, filed by him on December 31, 1941.

Operation

In the operation of the machine, filled containers which enter the machine over the ways 103 and on the chain belt 109 are intercepted by the timing screw 112 in the well known manner and are spaced along the ways so as to be properly received in the pockets of the star wheel C and transferred one by one thereby into the receiving pockets 20 in the main turret D.

As the main turret is rotated, the filled container supporting pads 21 thereof will be individually lifted by reason of the engagement of the stem rollers 23 with the lift portion 80 of the pad lifting and lowering cam 24. When the top of the lift portion 80 is reached the pads will be held in the fully elevated position by the dwell portion 81 of the cam which extends about approximately 30° of the circumference of the cam. In this elevated position the pads 21 support the containers with the upper feathered edges 79 of the cups 78 and the lower extremities of the electrodes 52 disposed at the normal fill liquid level L in the upper portion of said containers. If desired the lower extremity of one of the electrodes 52 can be positioned slightly below said level L.

As has been previously explained, whenever a container supporting pad 21 is lifted by the cam portion 80 onto the dwell crest 81 the latch plunger 103 will move into the pad stem recess 29 and latch the pad in said elevated position. Thus all containers having a normal or surplus fill will be held in the elevated position, and all containers filled with a surplus will be rendered normally filled containers by the drawing off of the surplus in the manner described.

It will be obvious that if a given container is filled above the normal level L, the surplus of liquid will flow over the feathered edge 79 of the cup 78 and into the interior of the cup where it will be drawn off by suction through the tube 74 and the ducts 69, 62 and 64 to be recovered in the surplus reclaiming reservoir herein before referred to. When the simple form of surplus draw off or suction tube 74a illustrated in Figure 11 is used and suspended in the container being tested to present its open lower end extremity at the level of normal fill, any surplus of fill will be similarly drawn off through this simple tube structure. It will also be obvious that in every container in which the level of the liquid fill is at or above the normal level L, the liquid will com-

plete an electrical circuit across the contacted electrodes 52 and effect an energizing of the solenoid 92, thereby causing the trip lever 96 and the latch tripping cam plate 99 carried thereby 5 to be pulled downwardly out of the path of movement of the latch levers 100, 102.

All underfilled or slack filled containers will fail to complete an electrical circuit across the electrodes 52 because of the fact that the deficient 10 level of the liquid will not reach these electrodes, and the latch tripping cam plate 99 will not be lowered and rendered ineffective with respect to such deficiently filled units but will be engaged by the particular latch lever or levers 100 and will 15 hold the particular latch or latches 103 away from the stem recesses 29. Consequently, when the stem rollers supporting such insufficiently filled containers reach the cam lowering portion 82 they will ride down said portion and return the 20 pads and the containers thereon to their lowered positions. While traveling around in this lowered position these insufficiently filled containers will engage the diverting cams 126 and be diverted into the rejection pass E to be discharged from 25 the machine by the block chain 130.

All properly filled containers will be held in the elevated, pad latched position by the latch equipments while traveling above the diverter cam equipment 126. Thus it may be said that the diverter cam equipment is normally effective and 30 is ineffective only when the latching equipment is allowed to remain set by retraction of the releasing cam 99. As previously described, completion of the control circuit through the electrodes by contact with liquid in the containers at the normal level L serves to hold the supporting pads and the containers thereon in the elevated position in which said containers ride over and 35 out of contact with the diverter cam equipment 126.

Each normally filled container and the pad supporting the same are held in the elevated position until the particular stem roller lies directly over the second crown crest 84 on the cam 24, 40 at which time the particular latch lever 100 will engage the stationary unlatching roller 106 which will rock said lever to effect a displacement of the latch plunger 103 and permit the particular pad 21 to move downwardly under control of the lowering portion 85 of said cam. Such properly filled containers will be transferred by the star wheel F from the main turret onto the feed away or delivery equipment G to be carried away by the link belt 141.

55 Any liquid dripping from the testing units as the properly filled containers are being transferred from the main turret will be caught in the catch pan 136.

It will be apparent that the latching equipments hold all pads and the properly filled containers supported thereon while they are traveling between the two cam crests 81 and 84, the diverting cam equipment 126 effective to divert deficiently filled containers being disposed between 60 these two cam crests. The circumferential spacing of the cam crests 81 and 84 provides ample time in which to efficiently draw off all liquid fill surpluses from the elevated containers. Only the deficiently filled containers are lowered into 65 position for being acted upon by the diverting cam means, and after such containers have been rejected from the machine by this cam means 126 the pads which had supported them will rise and fall idly over the second set of cam lifting and 70 lowering portions 83, 84, 85.

By reason of the provision of the particular form of testing units herein illustrated, a very efficient testing operation is effected because of the fact that substantially no vibration is set up in the liquid fill in the containers, and the testing operation is not affected by waves or bubbles in said liquid.

It is of course to be understood that the details of structure and arrangement of parts may be variously changed and modified without departing from the spirit and scope of my invention.

I claim:

1. In a machine of the character described, container supporting means, a tester unit including a support and suction tube and electrode means depending from said support, means for bringing about relative movement between said support and said supporting means to cause said tube and electrode means to depend in a container on the supporting means down to a predetermined normal liquid fill level in said container thereby to cause said electrode means to contact the liquid and said suction tube to draw off any surplus of fill, means for delivering properly filled containers from the machine, and means electrically controlled by completion of a circuit through said electrode means and the liquid fill for eliminating from said properly filled container delivering means any containers which are deficiently filled.

2. In a machine of the character described, container supporting means, a tester unit including a support and suction tube and electrode means depending from said support, means for bringing about relative movement between said support and said supporting means to cause said tube and electrode means to depend in a container on the supporting means down to a predetermined normal liquid fill level in said container thereby to cause said electrode means to contact the liquid and said suction tube to draw off any surplus of fill, a properly filled container delivery station, a deficiently filled container pass, means electrically controlled by completion of a circuit through contact of said electrode means and the liquid fill with liquid fill in a container for causing said container to be delivered at said delivery station, and means effective whenever said electrode means does not contact liquid fill in a deficiently filled container to cause said deficiently filled container to be delivered into said deficiently filled container pass.

3. In a machine of the character described, a rotary turret having thereon a plurality of filled container supporting pads and a plurality of overlying tester units all mounted in equidistantly spaced relation about the axis of the turret, each said unit including a support and suction tube and electrode means depending from each support, means for bringing about relative movement between the supports and the pads to cause said tube and electrode means to depend in containers on the pads down to a predetermined normal liquid fill level in said containers thereby to cause said electrode means to contact the liquid and said suction tube means to draw off any surplus of fill, a properly filled container delivery station, a deficiently filled container pass, means electrically controlled by completion of a circuit through contact of said electrode means and the liquid fill with liquid fill in containers to cause such containers to be delivered at said delivery station, and means effective whenever said electrode means does not contact liquid fill in a deficiently filled container to cause

said deficiently filled container to be delivered into said deficiently filled container pass.

4. In a machine of the character described, a rotary turret having thereon a plurality of filled container supporting pads and a plurality of overlying tester units all mounted in equidistantly spaced relation about the axis of the turret, each said unit including a support and suction tube and electrode means depending from each support, diverter cam means overlying the normal level of the pads and effective to engage containers on pads at said normal level and divert them from said pads to a place of rejected container deposit, a pad lifting and lowering cam portion effective to lift pads above said diverter cam means and having a crest portion disposed to cause said tube and electrode means to depend in containers on the pads down to a predetermined normal liquid fill level in said containers thereby to cause said electrode means to contact the liquid and said suction tube means to draw off any surplus of fill, means electrically controlled by contact of said electrode means with liquid fill in containers to hold the pads and containers thereon in which such liquid contact is made at the elevated position whereby properly filled containers will be caused to move over said diverter cam means toward a delivery station, and means effective to release the holding means when a container is underfilled, said lowering cam portion being effective to lower all said underfilled containers in which electrode and liquid contact is not made into position for being engaged and diverted by said diverter cam means.

5. In a machine of the character described, a rotary turret having thereon a plurality of filled containers supporting pads and a plurality of overlying tester units all mounted in equidistantly spaced relation about the axis of the turret, each said unit including a support and suction tube and electrode means depending from each support, diverter cam means overlying the normal level of the pads and effective to engage containers on pads at said normal level and divert them from said pads to a place of rejected container deposit, a pad lifting and lowering cam portion effective to lift pads above said diverter cam means and having a crest portion disposed to cause said tube and electrode means to depend in containers on the pads down to a predetermined normal liquid fill level in said containers thereby to cause said electrode means to contact the liquid and said suction tube means to draw off any surplus of fill, means electrically controlled by contact of said electrode means with liquid fill in containers to hold the pads and containers thereon in which such liquid contact is made at the elevated position whereby properly filled containers will be caused to move over said diverter cam means toward a delivery station, means effective to release the holding means when a container is underfilled, said lowering cam portion being effective to lower all said underfilled containers in which electrode and liquid contact is not made into position for being engaged and diverted by said diverter cam means, a second lifting and lowering cam portion spaced circumferentially from said first mentioned cam portion and having a crest of the same height and located beyond said diverter cam means, and means for releasing said holding means to permit the pads and properly filled containers thereon to be lowered on said second cam lowering portion and move on toward a delivery station.

6. In a machine of the character described, a

rotary turret having thereon a plurality of filled container supporting pads and a plurality of overlying tester units all mounted in equidistantly spaced relation about the axis of the turret, each said unit including a support and suction tube and electrode means depending from each support, diverter cam means overlying the normal level of the pads and effective to engage containers on pads at said normal level and divert them from said pads to a place of rejected container deposit, a pad lifting and lowering cam portion effective to lift pads above said diverter cam means and having a crest portion disposed to cause said tube and electrode means to depend in containers on the pads down to a predetermined normal liquid fill level in said containers thereby to cause said electrode means to contact the liquid and said suction tube means to draw off any surplus of fill, each said pad having a stem depending therefrom and vertically-slidably supported on said turret and equipped with a latch receiving recess, a spring pressed latch engageable in each stem recess for holding the respective pad at its elevated position, latch releasing means normally effective to release latches and permit pads and underfilled containers thereon to be lowered by said lowering cam portion so that said containers will be engaged and diverted by said diverter cam means, and means electrically controlled by contact of said electrode means with liquid fill in properly filled containers to render said releasing means ineffective whereby properly filled containers will be caused to move over said diverter cam means toward a delivery station.

7. A machine as defined in claim 6 in which said latch releasing means includes a latch tripping cam and a solenoid effective when energized by completion of an electrical circuit across the electrode means and through the liquid in an amply filled container to move said latch tripping cam to an ineffective position.

8. In a machine of the character described, a rotary turret having thereon a plurality of filled container supporting pads and a plurality of overlying tester units all mounted in equidistantly spaced relation about the axis of the turret, each said unit including a support and suction tube and electrode means depending from each support, diverter cam means overlying the normal level of the pads and effective to engage containers on pads at said normal level and divert them from said pads to a place of rejected container deposit, a pad lifting and lowering cam portion effective to lift pads above said diverter cam means and having a crest portion disposed to cause said tube and electrode means to depend in containers on the pads down to a predetermined normal liquid fill level in said containers thereby to cause said electrode means to contact the liquid and said suction tube means to draw off any surplus of fill, each said pad having a stem depending therefrom and vertically-slidably supported on said turret and equipped with a latch receiving recess, a spring pressed latch engageable in each stem recess for holding the respective pad at its elevated position, latch releasing means normally effective to release latches and permit pads and underfilled containers thereon to be lowered by said lowering cam portion so that said containers will be engaged and diverted by said diverter cam means, means electrically controlled by contact of said electrode means with liquid fill in properly filled containers to render said releasing

means ineffective whereby properly filled containers will be caused to move over said diverter cam means, and a second lifting and lowering cam portion spaced circumferentially from said

5 first mentioned cam portion and having a crest of the same height and located beyond said diverter cam means, and means for releasing latches holding properly filled containers in elevated position to permit them to be lowered by 10 said second cam lowering portion and move on toward a delivery station.

9. A machine as defined in claim 3 in which there are included container guiding walls partially surrounding the turret and defining said 15 deficiently filled container pass and said properly filled container delivery station, and a yieldable guide wall portion normally closing said pass and directing containers toward said delivery station and displaceable by containers delivered into said pass.

20 10. A machine as defined in claim 6 in which said diverter cam means has a clearance there-through to permit passage of said pad stems.

11. A machine as defined in claim 3 in which 25 means is included for independently adjusting the position of each suction tube and each electrode means.

12. A machine as defined in claim 3 in which 30 a common suction duct is disposed at the center of the turret and individual ducts are provided connecting all of the suction tubes with said common suction duct.

13. In a machine of the character described, a 35 rotary turret having thereon a plurality of filled container supporting pads and a plurality of overlying tester units all mounted in equidistantly spaced relation about the axis of the turret, each said unit including a support and electrode means depending from said support, 40 diverter cam means overlying the normal level of the pads and effective to engage containers on pads at said normal level and divert them from said pads to a place of rejected container deposit, a pad lifting and lowering cam portion effective 45 to lift pads above said diverter cam means and having a crest portion disposed to cause said electrode means to depend in containers on the pads down to a predetermined normal liquid fill level in said containers thereby to cause said electrode

50 means to contact the liquid, means electrically controlled by contact of said electrode means with liquid fill in containers to hold the pads and containers thereon in which such liquid contact is made at the elevated position whereby

55 properly filled containers will be caused to move over said diverter cam means toward a delivery station, means effective to release the holding means when a container is underfilled, said lowering cam portion being effective to lower all said underfilled containers in which electrode and liquid contact is not made into position for being

60 engaged and diverted by said diverter cam means, a second lifting and lowering cam portion spaced circumferentially from said first mentioned cam

65 portion and having a crest of the same height and located beyond said diverter cam means, and means for releasing said holding means to permit the pads and properly filled containers thereon to be lowered on said second cam lowering portion and move on toward a delivery station.

70 14. In a machine of the character described, a rotary turret having thereon a plurality of filled container supporting pads and a plurality of overlying tester units all mounted in equidistantly spaced relation about the axis of the turret, each

75

said unit including a support and electrode means depending from each support, diverter cam means overlying the normal level of the pads and effective to engage containers on pads at said normal level and divert them from said pads to a place of rejected container deposit, a pad lifting and lowering cam portion effective to lift pads above said diverter cam means and having a crest portion disposed to cause said electrode means to depend in containers on the pads down to a predetermined normal liquid fill level in said containers thereby to cause said electrode means to contact the liquid, each said pad having a stem depending therefrom and vertically-slidably supported on said turret and equipped with a latch receiving recess, a spring pressed latch engageable in each stem recess for holding the respective pad at its elevated position, latch releasing means normally effective to release latches and permit pads and underfilled containers thereon to be lowered by said lowering cam portion so that said containers will be engaged and diverted by said diverter cam means, and means electrically controlled by contact of said electrode means with liquid fill in properly filled containers to render said releasing means ineffective whereby properly filled containers will be caused to move over said diverter cam means toward a delivery station.

15. A machine as defined in claim 14 in which said latch releasing means includes a latch tripping cam and a solenoid effective when energized by completion of an electrical circuit across the electrode means and through the liquid in an amply filled container to move said latch tripping cam to an ineffective position.

16. In a machine of the character described, a rotary turret having thereon a plurality of filled container supporting pads and a plurality of overlying tester units all mounted in equidistantly

spaced relation about the axis of the turret, each said unit including a support and electrode means depending from each support, diverter cam means overlying the normal level of the pads and effective to engage containers on pads at said normal level and divert them from said pads to a place of rejected container deposit, a pad lifting and lowering cam portion effective to lift pads above said diverter cam means and having a crest portion disposed to cause said electrode means to depend in containers on the pads down to a predetermined normal liquid fill level in said containers thereby to cause said electrode means to contact the liquid, each said pad having a stem depending therefrom and vertically-slidably supported on said turret and equipped with a latch receiving recess, a spring pressed latch engageable in each stem recess for holding the respective pad at its elevated position, latch releasing means normally effective to release latches and permit pads and underfilled containers thereon to be lowered by said lowering cam portion so that said containers will be engaged and diverted by said diverter cam means, means electrically controlled by contact of said electrode means with liquid fill in properly filled containers to render said releasing means ineffective whereby properly filled containers will be caused to move over said diverter cam means, and a second 30 lifting and lowering cam portion spaced circumferentially from said first mentioned cam portion and having a crest of the same height and located beyond said diverter cam means, and means for releasing latches holding properly filled 35 containers in elevated position to permit them to be lowered by said second cam lowering portion and move on toward a delivery station.

ALFRED L. KRONQUEST.
